UNITED STATES PATENT OFFICE.

WALTHER MATHESIUS, OF CHICAGO, ILLINOIS.

WATER-COOLED BOSH PLATE.

Application filed July 19, 1920. Serial No. 397,430.

To all whom it may concern:

Be it known that I, WALTHER MATHESIUS, a citizen of the United States, residing at Chicago, in the county of Cook and State of Illinois, have invented certain new and useful Improvements in Water-Cooled Bosh Plates, of which the following is a specification.

My invention relates to cooling plates for use in connection with blast furnaces and blast furnace operations. These cooling plates are inserted in the walls of blast furnaces and form a part of such walls and have water constantly circulating through them for cooling purposes. Because they are placed in the walls of the furnace, usually around the hearth or bosh of the furnace, they are commonly called bosh plates.

The principal object of my invention is the provision of a cooling plate which is adapted to withstand a maximum amount of external pressure due to the masonry structure in which the plate is incorporated and which will afford a free circulation of water in said plate.

Another object of my invention is the provision of a cooling plate which can be easily manufactured and which, when manufactured, will be without holes in the baffles in said plate, which has been a common expedient in the casting operation in the manufacture of these cooling plates heretofore in order that the core material could be withdrawn from the plates after the casting operation is completed.

Another and further object of my invention is the provision of a cooling plate which, while being cast, has sufficient passages for the quick and complete escape of gases from the cores during the pouring operation and also during the cooling of the metal. As is well known, if the gas does not escape freely from the cores during the pouring operation the metal will be uneven in the thickness and thus weakened, or will be porous, thus allowing for leakage of the water through the walls of the plate.

Another and further object of my invention is the provision of a cooling plate which is strong in design and in which the baffles are disposed in such manner that the maximum amount of strength is afforded without crushing the cooling plate or causing transverse ridges to be formed therein which resist the removal of the baffle plates from the furnace wall without the destruction of

either the plate or damage to the blast furnace wall.

Another and further object of my invention is the provision of a bosh plate having a uniform water circulation throughout the entire plate, thereby obtaining a uniform cooling action, and also eliminating the danger of air pockets forming in said plates, especially nearest the side of its highest temperature.

Still another object of my invention is the provision of a cooling plate in which refuse or sediment will not easily become lodged but will be carried out by the current of water passing through the said plate and the clogging up of the water passages reduced to a minimum, but if the water passages should become clogged the sediment can be removed and the cooling plate kept in such condition that the water circulation is not retarded because of sediment which might collect in the said cooling plate.

These and other objects of my invention will be more readily and better understood by those skilled in the art by reference to the accompanying sheet of drawings and in which:

Figure 1 is a longitudinal sectional view of my improved invention; and

Figure 2 is a cross-sectional view on line 2—2 of Figure 1.

Referring now specifically to the drawings, it will be seen that the present bosh plate includes a back wall 10 and integrally formed therewith lugs 11, 11, the said lugs 11 having openings 12, 12 therethrough which provide means for pulling the cooling plate out of the furnace wall. Side walls 13, 13 are provided, also a nose or forward end wall 14 and top and bottom walls 15 and 16 respectively, the said side walls 13, 13 and the top and bottom walls 15 and 16 being cast integrally with said back wall 10. An inlet 17 through the back wall 10 is provided through which water is forced into the cooling plate and an outlet 18 being provided through which the water passes out of the plate, openings 19, 20 are also provided in the back wall 10 of the plate which, when the plate is in operation, are normally closed by means of plugs. The openings 17, 18, 19 and 20 provide means for the escape of gases from the core material during the casting operation, and also for the removal of the core material from the plate after casting, and also provide means for inspecting

and cleaning out the bosh plate while it is in service in the blast furnace wall. Cast integrally with the back wall is an inwardly extending wall or baffle 21, the said baffle 21 being formed integrally also with the top wall 15 and bottom wall 16 of the plate. The said wall 21 extends inwardly towards the nose of the baffle and within a short distance of the wall 14, and then makes a right angled turn and extends transversely across the said plate at its nose end and terminates a short distance from the side wall 13 of the plate. A baffle or wall 22 beginning with the side wall 13 extends transversely across the said cooling plate for approximately one-half the width of the said plate and then makes a right angled turn in a direction towards the back wall 10 of the plate, and terminates a short distance from the said back wall 10. A third wall or baffle 23 extends inwardly from the back wall in a direction parallel with the side wall 13 and terminates short of the wall or baffle 22. It will thus be understood that a passage 24 is formed between the wall 21 and the side wall 13 and end wall 14 of the cooling plate. A passage 25 is formed between the wall or baffle 21 and the wall 22. Another passage 26 is formed between the wall 22 and the wall 23, while another passage 27 is formed between the wall 23 and the side wall 13 of the cooling plate. During the operation of the blast furnace, when the cooling plate is in operation, a current of water is directed into the plate through the opening 17, passes through the passage 24, thence around the end of the wall 21 and into the passage 25, thence around the wall 22 and into the passage 26, thence around the end of the wall 23 and into the passage 27 and out through the opening 18.

It will thus be understood that in operation a current of water is kept passing through the cooling plate, which I prefer to be made of copper or any other metal having a high heat conductive property, although I do not wish to be understood as limiting myself to this particular kind of metal for the manufacture of these plates.

By my arrangement of baffles, I provide a continuous and unobstructed water circulating passage which is of substantially uniform cross section, and this passage occupies the entire interior area of the bosh plate to the exclusion of any pockets and dead water space, and therefore there is no opportunity for sediment or other impurities contained in the water to lodge in the cooling plate. By the disposition of the baffles 21, 22 and 23 the top and bottom walls 15 and 16 are reinforced, and consequently external pressure brought to bear upon the bosh plate from the surrounding furnace structure may in extreme cases result in longitudinal corrugations being formed in said top and bot-

tom walls, but such longitudinal corrugations will not interfere with the convenient endwise removal of the bosh plate from the furnace wall. This is a distinct advantage over conventional forms of bosh plates wherein the baffles are disposed transversely of the device, for the reason that in such devices the top and bottom walls are not properly supported and strengthened, therefore the external pressure of the furnace structure will produce transverse corrugations in the top and bottom walls of the bosh plate, which corrugations will prevent the endwise removal of the bosh plate from the furnace wall.

The present baffle arrangement provides a single water passage of substantially uniform cross section occupying the entire interior area of the bosh plate compelling a uniform rate of water flow and thus preventing an accumulation of sediment. The absence of dead spaces and pockets promotes uniform heat transfer from the bosh plate to the water, thereby avoiding local overheating, steam pockets, mud accumulations and consequent destruction of the bosh plate. The longitudinal baffles are in the load carrying area and provide great strength against external pressure of the surrounding furnace structure, and these baffles also prevent the formation of transverse corrugations such as are produced in and prevent the removal of other types of bosh plates which have transverse baffles in their load carrying areas. The present arrangement of transverse baffles in the nose end of the bosh plate, which is the high temperature end thereof, permit free contraction and expansion and uniform and effective cooling in that they do not tie the top and bottom walls of the bosh plate to the inner end wall at the nose of the plate. The combination of the transverse baffles, the longitudinal baffles and the clean-out openings in the back wall of the bosh plate provides for ready ventilation of core material during the casting operation, easy removal of the core material after casting and convenient and complete accessibility of water passages for removing sediment therefrom while the plate is embedded within the masonry structure of the furnace.

While I have described more or less precisely the details of construction, I do not wish to be understood as limiting myself thereto, as I contemplate changes in form and the proportion of parts and the substitution of equivalents as circumstances may suggest or render expedient, without departing from the spirit or scope of my invention.

I claim:

A bosh plate comprising a substantially rectangular box tapered from its outer end to its inner end and having a back wall provided with a water inlet at one end thereof and a water outlet at the opposite end of the

back wall, said back wall also being provided with intermediate plugged openings, a baffle plate leading from the back wall and terminating short of the opposite wall and 5 located between the inlet opening and the adjacent plugged opening, said baffle having a terminal extension disposed at substantially right angles to the baffle and leading towards the opposite side of the bosh plate, 10 a second baffle plate leading from the back wall and disposed between the outlet opening and the adjacent intermediate opening, and a transverse baffle disposed between the second mentioned baffle and the extension of 15 the first mentioned baffle and leading from

one of the side walls of the bosh plate, said transverse baffle having a terminal extension disposed at substantially right angles thereto and lying opposite the interval between the plugged openings, said baffles defining a 20 continuous undivided and unobstructed water passage from the inlet opening to the outlet opening and occupying the entire interior area of the bosh plate, said water passage being of substantially uniform cross 25 sectional area throughout its length.

Signed at Chicago, Illinois, this 9th day of July, 1920.

WALTHER MATHESIUS.
